OF ONE-HALF TO EINAR WAHLSTRÖM, OF VITTINGFOS, NORWAY.

AUTOMATIC WOOD-GRINDING MILL.

1,246,944.

Specification of Letters Patent. Patented Nov. 20, 1917.

Application filed January 25, 1916. Serial No. 74,091.

To all whom it may concern:

Be it known that I, PEDER CHRISTIAN SCHAANNING, a citizen of Norway, residing at Vindern pr. Christiania, Norway, have 5 invented new and useful Improvements in Automatic Wood-Grinding Mills, of which the following is a specification.

Several constructions of so-called automatic apparatuses for grinding wood for 10 the manufacture of wood pulp or the like have already been designed. In the type most known one or more grinding boxes are arranged into which the wood blocks, when the emptied box is opened, have to rush 15 down so as to refill the box, whereafter a pressing plate or a similar member which is connected with a hydraulic piston, forces the blocks against the stone. Each time a box has become empty, it is again opened 20 automatically, and so on.

This construction consequently is based upon the assumption, that the wood blocks by their own weight will fall down freely into the empty box which has been opened. 25 Practice has taught, however, that such falling-down frequently will fail, because the blocks often form a "bridge" or a self-carrying arch, so that they will not refill the grinding box therefor, within which the 30 pressing plate continues to travel back and forward without any use until the inspector's attention is directed to the said fact and the error is removed by hand. Such apparatuses therefore are not quite automatic in operation. 35

Apparatuses therefore have been constructed, in which the wood blocks are forced against the grinding-stone by means of endless chains with projections acting 40 upon the long sides of blocks, or by means of grooved or ribbed rolls acting upon the end faces of the blocks. Neither such apparatuses have been satisfactory, partly because the designer has not paid sufficient 45 regard to the fact, that the wood blocks forming parts of logs are present in considerably varying sizes, as not only the diameter but also the length may vary to a considerable extent. Moreover there exist 50 half blocks, props, pins and sometimes blocks of half length and, last but not least, crooked blocks or log parts.

From these facts it is evident that an 55 automatic grinding apparatus must possess a very great ability of accommodating itself

to the conditions varying in actual practice, and on account hereof there has not heretofore—so far as the present applicant knows—existed any satisfactory solution of the problem. 60

The present invention has for its object to provide an automatic grinding apparatus, which is constructed so as to pay most possible regard to the practical conditions and which therefore may fulfil all requirements 65 with regard to a quite automatic operation.

A constructional form of the apparatus is illustrated in the accompanying drawings, in which:

Figures 1 and 2 are vertical sections taken 70 at planes perpendicular to each other.

The grinding stone —1— is mounted as usual on a shaft —2— and its lower half projects down into the outlet channel —3—. Against the stone are conducted, more or less 75 radially, one or more block columns, only one of which is shown in the drawing for the sake of simplicity. This block column shall be rectilinear, at all events on the portion upon which the feeding members 80 act. The column may be guided in different manners. In the following only the method is described which is thought to be the most suitable one.

The invention is based upon automatically operating grinding apparatuses of the kind in which the feeding of the wood blocks against the stone takes place by means of movable parts the catching and feeding members of which act upon the end 85 faces of the blocks, and the special characterizing feature of the invention consists in the fact that the catching and feeding members are carried and journaled by a frame fed rectilinearly forward against the 90 grinding-stone in such a manner that they are able to perform an independent tightening or clamping movement in the cross direction of the block column toward the said end faces, in order to transmit the pressing 95 force of the frame safely to the inner portion of the column.

In this manner the catching members may accommodate themselves to blocks of different length always existing, which cannot be obtained by grooved rolls or by catching members attached fixedly to endless chains. 105

According to this invention two opposite side walls of the block column channel are limited or formed by four idle endless chains 110

—4—, one pair being arranged on either side. These chains travel over upper and lower disks —5, 6—, but contrary to endless chains in previous automatic grinding apparatuses they have nothing to do with the feeding of the block column. Therefore the chains are not provided with any projections and are not specially driven, they being only taken along by the column fed forward by the catching members. The chains here have only to form movable wall portions of the block channels so that the block column need nowhere slide on fixed walls. There otherwise, under the high pressures, would be great friction and as a consequence thereof displacements within the block mass, because it would be impossible to lubricate between the blocks and such walls.

20 But in order to enable the inner portions of the chains to act as unyielding walls the chains on their outer side are supported by strong H-irons —7—, which at their lower parts are attached to the grinding box and 25 at their upper part are supported by a surrounding frame —9—. These H-irons carry the bearings for the disks —5, 6—. The inner parts of the chains —4— slide tightly upon the irons —7—, and the contacting 30 portions of said members may be lubricated with graphite or other lubricant, which thus will not reach the block column.

The feeding device proper may consist of two grates —10— carrying the catching 35 members and arranged on either block face side, consequently in planes perpendicular to the moving planes of the chains —4—. These grates contain preferably a large number of independently movable catching members —11—, which in the drawing are indicated diagrammatically in the form of inclined sharp arms catching the end faces of the blocks (see Fig. 1) and adapted to be pressed against the blocks by hydraulic 40 or other means (not shown). Preferably the catching members are arranged in more horizontal and vertical rows as indicated in Fig. 2. These two grates are attached to a strong rectangular frame —12—, which is 45 movable to and fro upon four stationary pillars —13—, each of the four guidings of the frame being constructed as a hydraulic cylinder —14—, the piston —15— of which is fixed on the pillar —13— (Fig. 1).

50 Assuming the block column channel being filled from above (in Fig. 2 the column being interrupted in order to illustrate the construction of the grates) and the feeding frame —12— being in its uppermost position as shown, water under pressure is pumped into the bottom space of the cylinders —14— beneath the pistons —15—. All 55 cylinders, the frame —12— and both grates —10— therefor will travel slowly downward. During this movement the catching

members —11— carried by the frame automatically exert independent tightening or clamping action upon the blocks of the column, with which they contact, in a direction transverse to the axis of the column. This is due to their normal inclination; the downward force which is applied by the feeding frame to the outer ends of the catching members causes them to tend to assume horizontal positions, since their inner ends are 70 caught in the respective blocks of the column. Consequently, the last-mentioned ends press inwardly toward the center of the column with great force, which serves to transmit the pressing and feeding force of the frame 75 to the innermost portion of the column. All of the blocks receive this application of force, whether they be long or short, or of odd shapes. After the catching members 80 thus engage the end faces of the blocks they carry the whole block column slowly downward against the stone —1—. The members retain their hold until the frame has reached its lowermost position. Now the supply of water under pressure to the cylinders —14— 85 is automatically reversed by well-known mechanisms (not shown); so that the water under pressure now enters the cylinders above the pistons —15—. The frame —12— with the grates —10— therefor moves upward, the catching members let go their hold upon the blocks and the grinding is stopped 90 during the short period as the frame —12— is now, practically without any resistance, moving rapidly up to its uppermost position, in which the supply of water under pressure is again automatically reversed. In order to prevent the block column during 95 this upward movement from being lifted along upward, the frame —9— may be provided with movable counter-catches or other stopping members as indicated at —16—. The frame —12— thereupon begins a new working movement downward in the same manner as before. 100

It will be seen that the whole operation takes place quite automatically, and the block column is carried uniformly and safely against the stone without the blocks, from the introduction uppermost even to the stone 115 innermost, needing to undergo any free fall or shift their mutual place in any way. However, the block channel without causing any great damage may of course be curved on the portion located above the frame 120 —12—, although such a construction should be avoided, if possible.

In general, the details of the invention may be varied to a great extent without departing from its essential idea.

Having now described the invention, what I claim as new and desire to secure by Letters Patent is:

1. In an apparatus for grinding wood in the manufacture of pulp, the combination of 130

- a grinding member, a guide for a column of wood blocks leading to the grinding member, a feeding frame mounted for movement in a path parallel to the said guide, means 5 for moving the frame, and catching members carried by the frame and mounted for independent movement thereon transverse to the path of movement of the frame for engagement with the blocks of the column.
- 10 2. In an apparatus for grinding wood in the manufacture of pulp, the combination of a grinding member, a guide for a column of wood blocks leading to the grinding member, a feeding frame mounted for movement 15 in a path parallel to the said guide, means for moving the frame, and catching members mounted on the frame for independent movement thereon transverse to the path of movement of the frame for engagement 20 with the blocks of the column, each catching member being inclined downwardly toward the block column and having its upper end connected to the feeding frame.
3. In an apparatus for grinding wood in 25 the manufacture of pulp, the combination of a grinding member, a guide for a column of wood blocks leading to the grinding member, a feeding frame surrounding the said guide, movable hydraulic cylinders carried 30 by the frame, stationary pillars passing through the heads of the respective cylinders, a piston positioned within each cylinder and fixed upon the corresponding pillar, and catching members carried by the frame for 35 engagement with the blocks of the column.
4. In an apparatus for grinding wood in 40 the manufacture of pulp, the combination of a grinding member, a guide for a column of wood blocks leading to the grinding member, a feeding frame mounted for reciprocation 45 in a path parallel to the said guide, means for moving the frame, catching members carried by the frame for operative engagement with the blocks of the column during movement of the frame toward the

grinding member, and catching members provided on the said guide for engagement with the blocks of the column to secure the latter against retrograde movement.

5. In an apparatus for grinding wood for 50 the manufacture of pulp, the combination of a grinding member, a guide for a column of wood blocks leading to the grinding member and consisting of endless chains arranged idly along the column so that their 55 inner reaches constitute the opposite walls of the guide and support the side faces of the blocks, the said reaches being adapted to be carried along with the column in its feeding movement, stationary reinforcing bars 60 supporting the said inner reaches of the chains, and independent means for feeding the block column against the grinding member.

6. In an apparatus for grinding wood for 65 the manufacture of pulp, the combination of a grinding member, a guide for a column of wood blocks leading to the grinding member and consisting of endless chains arranged idly along the column so that their 70 inner reaches constitute the opposite walls of the guide and support the side faces of the blocks, the said reaches being adapted to be carried along with the column in its feeding movement, stationary reinforcing 75 bars supporting the said inner reaches of the chains, and feeding means for the column comprising a frame surrounding the guide, means for moving the frame along the guide, and independently movable catching members 80 carried by the frame and disposed for engagement with the end faces of the blocks of the column.

In testimony whereof I have signed my name to this specification in the presence of 85 two subscribing witnesses.

PEDER CHRISTIAN SCHANNING.
